UNITED STATES PATENT OFFICE.

FRANCIS T. JOHNSON, OF CHICAGO, ILLINOIS

IRONING-MACHINE.

1,270,297.

Specification of Letters Patent. Patented June 25, 1918.

Application filed June 16, 1917. Serial No. 175,077.

To all whom it may concern:

Be it known that I, FRANCIS T. JOHNSON, a citizen of the United States, residing at Chicago, in the county of Cook and State of Illinois, have invented a certain new and useful Improvement in Ironing-Machines, of which the following is a specification.

My invention relates to improvements in ironing machines or mangles. It has for one object to provide a new and improved form of ironing machine or mangle wherein the ironing or guiding rollers may be easily and conveniently moved toward and from the heating roller. Another object is to provide a new and improved structure whereby the article being ironed may be held upon the roller and exposed to the ironing pressure for a maximum period. Another object is to provide means whereby a relatively large number of small rollers may be employed to hold the work against the ironing roller and whereby the number may be varied depending upon the amount of work being done, the size of the ironing roller and the general purposes of the machine. Other objects will appear from time to time in the specification.

My invention is illustrated more or less diagrammatically in the accompanying drawings wherein—

Figure 1 is an end elevation with parts in section:

Fig. 2 is a detail of the end elevation with parts omitted showing the rollers in a different position:

Fig. 3 is a plan view of the rollers:

Fig. 4 is a section along the line 4—4 of Fig. 1.

Like parts are indicated by like letters in all the figures.

The ironing machine has a supporting and foundation frame at either end. These frames are identical and the support and connection of the different parts and their mounting in the frame is identical so that it will be sufficient to describe only one end of the machine although in Fig. 3 I have illustrated both ends.

A is an end frame provided with the usual supporting legs A¹ A¹ held together at their bottom by the cross pieces A². A³ A³ are bearings on the frame A in which is rotatably mounted a shaft A⁴ driven by means of a belt wheel A⁵ and belt A⁶ from any suitable source of power. Intermediate the ends of this shaft and between the bearings

A³ A³ is a worm A⁷ in mesh with a worm gear A⁸ keyed to a driving shaft A⁹. On the inner end of this shaft A⁹ is a driving pinion A¹⁰. 20

B is a bearing mounted in the frame A. Rotatably mounted thereon is a hollow sleeve B¹ which extends inwardly and carries a perforated drum B². Mounted on this drum is a hollow ironing roll B³. The 65 perforations B⁴ in the drum are provided so that air may enter the drum to permit combustion of the gas which is fed thereinto through the gas pipe B⁵. This gas pipe is provided with burner holes B⁶ inside of the 70 drum so that the gas may be lighted and the ironing roller be heated thereby. This ironing roller is a perfectly smooth, hard cylindrical iron roller with a smooth, clean surface across which material to be ironed may 75 be fed. B⁷ is a cap surrounding the outer end of the bearing B and substantially closing the sleeve B¹ being perforated just large enough to permit the pipe B⁵ to pass in. B⁸ is a gear mounted on the hollow shaft or 80 sleeve B¹ in mesh with a pinion A¹⁰ so that the ironing roller may be driven from the power sources as indicated. B⁹ is a working platform supported on the arms B¹⁰ from the frame A and terminating adjacent 85 the working face of the ironing roller in a thin overhanging metallic lip B¹¹ provided for the purpose of guiding the material from the working platform over on to the ironing roller. 90

Grouped about the ironing roller are a series of smaller separate holding or guiding rollers. I have shown two but there may be more or less as the case may be, my arrangement being such that the number is not limited, the operation being the same in every case. These rollers are identical, their mounting and supporting arrangements are identical and the description of one will suffice for all. 95

C, C are lugs extending outwardly an equal distance from the frame A. C² C² are hangers pivoted at C³ on these lugs. These hangers contain bearing seats C⁴ in which blocks C⁵ are slidably mounted. 100 These blocks form bearings for the shafts C⁶ upon which the guiding rollers C⁷ are mounted. Springs C⁸ are interposed between these blocks and adjustable thumbscrews C⁹ whereby the blocks are yieldingly 11 thrust inward.

Each hanger is bifurcated as at D, the

- 22
- bifurcation straddling the stop member D¹ projecting from the bearing B. D² is a roller adapted to contact with this stop member. It is mounted on a shaft D³ which 5 shaft projects outwardly in front of the hanger and carries a cam roller D⁴. This cam roller slides in a cam slot D⁵ which slot is in a cam plate D⁶ mounted for rotation about the bearing B. The rollers D⁴ are 10 mounted on the spacing sleeves D⁷ to prevent binding and the cam plate is held in position by the cap B⁷ and the caps D⁸ on the shafts D³. D⁹ is a handle, there being one at either end of the machine connected 15 by cross pieces D¹⁰ D¹¹ whereby the operator may rotate the cam to raise and lower the hangers and thrust the guiding and holding rollers in or throw them out of contact with the ironing roller.
- 20 The guiding rollers C⁵ are covered with a number of layers of fabric or cloth E, which may be put on separately or wound round and round as the case may be. At any rate they provide a soft and more or 25 less yielding covering for the guide rollers, which covering may be removed or may be decreased in thickness or other thickness added to at the will of the operator and depending upon the circumstances of the case.
- 30 Rigidly attached to the shaft C⁴ are a series of gears E¹ in mesh with the gear B⁸, so that the guiding rollers are positively driven by the gear which drives the ironing roller. I have shown the relation between the gears 35 E¹ and B⁸ such that the peripheral speeds of the guiding and the ironing rollers will be about the same, though a change in the diameter of the guiding roller C⁵ by the addition or subtraction of layers of the covering material would slightly disturb this 40 situation.

It will be evident that while I have shown in my drawings an operative device, still many changes might be made both in size, 45 shape, and arrangement of parts, without departing materially from the spirit of my invention, and I wish, therefore, that my drawings be regarded as in a sense diagrammatic.

50 The use and operation of my invention are as follows:—

The operator first lights the gas in the head ironing roller. He then places the work which is to be ironed upon the ironing or supporting table, and spreads it out or folds it carefully. He then starts the motor which drives or rotates the ironing roller, after that roller has been sufficiently heated. He lays his work upon this roller, 55 and then by manipulating the handle, rotates the cam plate so as to draw the guiding and compressing rollers down against the work and against the ironing roller. These guiding and compressing rollers are 60 driven as indicated in unison with the iron- 65

ing roller at such a rate of speed that their peripheral velocities are substantially the same, although of course no harm would be done by a slight difference in velocity, because the ironing roller being smooth would merely slip over the work while the work being engaged by the fabric or cloth covering on the guiding roller, would be propelled by the guiding rollers and controlled in speed by them. 70

The work passes around the ironing roller, for a greater or less distance depending upon the number of guiding rollers in place. It might be possible to carry the work back almost all the way around the ironing roller. 80 Ordinarily this is not done, however, and the work is dropped down after passing under the two rollers which I have shown.

If, for any purpose, the operator wishes to release the work while it is partly through 85 the machine, he needs only to manipulate the handle to raise all the guiding rollers out of contact with the ironing roller, and when the pressure is released, there is obviously no driving force which will tend to carry 90 the work through.

The adjustment of the guiding rollers is provided by means of the rotating hand or thumb screws acting against the springs which force the bearing block inwardly. 95 This spring arrangement is needed so as to compensate for changes in thickness of the work, and also so as to compensate for changes in the diameter of the guiding roller since these diameters may change 100 owing to the fact that the guiding rollers are covered by a cloth or fabric covering the surface as indicated. This may mat or pack down or it may be changed by the operator. In any event it 105 becomes necessary to provide a yielding pressure whereby any differences in diameters or any difference in the thickness of the work may be compensated for.

Attention is called to the fact that the 110 cam slot at both ends are normal to the plane of movement of the roller for a sufficient distance to insure that there will be no tendency toward a release of the cam. In other words, it is so arranged that when 115 the rollers are in the inoperative position they stay there, and when they are in the working position they also stay there; thus no separate means are needed for holding the rollers in to the work, or for holding 120 them away from the work.

In view of the fact that the supporting means for each of the guiding rollers is separate from the other, it is clear that, by changing the number of slots in the cam 125 plates, it would be possible to have a larger or a smaller number of guiding rollers. Each of these guiding rollers would in this case operate separately and be separately moved toward and from the ironing roller 130

by the movement of the cam plate, and thus the size of the rollers might be changed so as to have a large number grouped around the ironing plate, or a small number as the 5 case may be, and because these rollers are all moved along radial lines toward and from the ironing roller, they do not take up any room more than the room needed for the roller itself, and do not interfere with 10 the operation of one another.

I claim:-

An ironing machine comprising an ironing roller and a guiding roller in opposition to the ironing roller, means for moving said 15 guiding roller toward and from the ironing

roller consisting of a rotatable ~~rotated~~ cam member having an inclined cam slot portion and at either end of such inclined cam slot a cam slot portion normal to the line of movement of the roller such portions serving 20 to lock the guiding roller in place in either the operative or the inoperative position.

In testimony whereof, I affix my signature in the presence of two witnesses this 28th 25 day of May, 1917.

FRANCIS T. JOHNSON.
